Primary Examiner — Ricky Pham

(57) **CLAIM**

The ornamental design for a barbecue griddle, as shown and described.

DESCRIPTION

FIG. 1 is a perspective view of a barbecue griddle showing my new design;

FIG. 2 is a top view of the griddle;

FIG. 3 is a front elevational view of the griddle;

FIG. 4 is a right side elevational view of the griddle;

FIG. 5 is a rear elevational view of the griddle; and,

FIG. 6 is a bottom perspective view of the griddle.
The broken lines shown in the drawings are for illustrative purposes only and form no part of the claimed design.
